INSULATED SUCKER ROD AND TUBING TO
PREVENT ELECTROLYSIS AND CORROSION

Samuel M. Holcombe, Tulsa, Okla.

Application August 28, 1950, Serial No. 181,851

3 Claims. (Cl. 308—4)

1

This invention relates to parts in an oil well subject to corrosion and electrolytic action of the well fluids and particularly to the tubing and sucker rods of a well. It is known that when wells produce fluids containing electrolytic and corrosive elements such as salts, sulphur dioxide, and hydrogen sulphide, the rods and tubing are of relatively short life and are constantly subject to failure. When such elements are present in the well fluids, electrolytic and corrosive action takes place at the more vulnerable areas such as the joints and particularly the threads thereof. Also rubbing of the rods on the tubing provides points where the electrolytic action concentrates. Consequently, stress in the rods at these points causes them to give away in operation and results in expensive fishing jobs.

The objects of the present invention are therefore to protect the tubing and sucker rods by substantially eliminating electrolysis between the sucker rods and tubing; to provide for the maintenance of tight joints and thereby prevent contact of the well fluids with the threads; to provide the sucker rod string with insulating couplings; to provide selected couplings with guides to prevent contact of the rods with the tubing; to provide the tubing and/or sucker rods with an electrically insulating covering or skin whereby the sucker rods may be manufactured from the tougher but more easily attacked metals; to provide insulating guides having flow passages through which the well fluids pass the couplings with a minimum of resistance to the flow and yet provide ample bearing contact of the insulating material with the wall of the tubing, and to dampen vibrations of the rods.

In accomplishing these and other objects of the invention as hereinafter pointed out, I have provided improved structure, the preferred form of which is illustrated in the accompanying drawings wherein:

Fig. 1 is a longitudinal section through a string of well tubing and sucker rods embodying the features of the present invention.

Fig. 2 is an enlarged longitudinal section through the tubing and one of the coupling members particularly illustrating the insulating guide thereon.

Fig. 3 is a cross-section on the line 3—3 of Fig. 2.

Fig. 4 is a section through one of the standard sucker rod couplings modified in accordance with the present invention.

Fig. 5 is a cross-section through one of the rods on the line 5—5 of Fig. 4.

2

Fig. 6 is an enlarged section through one of the tubing couplings.

Fig. 7 is a fragmentary section through one of the sucker rod couplings.

Referring more in detail to the drawings:

1 designates a bore hole of a well extending from the top of the ground to a formation 2 producing, for example, petroleum oil. Extending downwardly in the bore hole is a tubing 3 carrying a pump 4 and a strainer section 5 through which the oil is admitted to the pump. The pump 4 includes a standing valve 6 seated in the lower end of the pump cylinder 7, and reciprocable in the cylinder is a piston 8 carrying a working valve 9 to which a string of sucker rods 10 is connected. The string of sucker rods continue upwardly through the tubing for reciprocation above ground by means of a suitable pumping jack (not shown). The tubing 3 is composed of a series of pipe sections 11 interconnected by couplings 12 having internal threads 13 engaging external threads 14 on the adjacent ends of the pipe sections. The sucker rod string includes a plurality of sucker rods 15 having rod-like body portions 16 formed at the ends to provide upsets 17 and 18 on the respective sides of wrench-engaging faces 19. Also formed on the ends of the sucker rods are shoulders 20 and tapered pins 21 having external threads 22 which engage in the threaded sockets or boxes 23 and 24 at the respective ends of rod couplings 25. The threaded sockets or boxes may be formed at the ends of a continuous bore 26 if desired. The strainer 5 usually consists of one or more sections of pipe having perforations for admitting the well fluids to the pump. The structure thus far disclosed is conventional of sucker rods and tubing used in the pumping of oil wells. Usually crude petroleum contains corrosive and electrolytic fluids that attack the metals of the sucker rods and tubing and cause fatigue failures, particularly at the threaded joints of the couplings.

The electrolytic action produced by the presence of electrolytes contained with the petroleum causes electric currents to flow from the rods to the tubing and results in rapid pitting and reduction of the cross-sectional area of the rods so that the rods are subject to failure under stress and especially repetitions of stresses as occur in loading and unloading of the rods incidental to reciprocation thereof.

As above pointed out, such wells are usually out of plumb due to the impossibility of drilling 55 a straight bore hole with the result that the

string of sucker rods rubs upon the tubing at various points throughout the depth of the well. This rubbing action during reciprocation of the rods effects rapid wear of the tubing and rods which also adds to the hazard and increases fatigue failures promoted by electrolytic and corrosive effects of the fluid.

In carrying out the present invention, I have provided a tubing and sucker rod, tubing and coupling construction which eliminates the above difficulties by preventing any direct contact of the metal with the well liquids. This is effected by provision of the rods, tubing, and couplings with an electrically insulating coating or skin to prevent passage of the electrolytic currents that cause deterioration. Each section of pipe composing the string of tubing is provided with a lining-like coating 27 on the inner surface and extending the full length thereof. The coating may be formed of any suitable insulating material that is resistant to action of the well liquids. For example, one of the synthetic rubbers commonly known as "neoprene" or the equivalent which is applied to the inner surface by dipping the sections of pipe into a liquid body of self-vulcanizing synthetic rubber.

The sections of sucker rod are similarly coated as indicated at 28 with the exception of the threads the pins 21.

The standard sucker rod couplings 25 are also preferably covered with a similar coating 29. Therefore, when the sections of sucker rods are connected together by couplings, the entire surface of the entire string is electrically insulated along the entire length thereof to prevent passage of electrolytic currents from the rods through the electrolytic content of the well fluids to the tubing as long as the pins 22 and boxes are tightly engaged. To assure tight connections of the threads, the bore of the couplings are closed midway the length thereof by plugs 30 which are threaded into the bore and form backing for blocks 31 of rubber or preferably synthetic resilient material. The blocks are of ample thickness relatively to the depths of the sockets and length of the pins so that when the pins of the rods are completely engaged within the sockets of the couplings, the resilient material is compressed to provide a resistance to backward turning of the rods and thereby assure sufficiently tight joints to prevent intrusion of the well liquids. The material from which the blocks are formed is of sufficient resiliency so that when the rods are to be uncoupled, they will yield sufficiently to permit turning of the rods. To prevent the end of the rod from tearing the surface of the blocks, suitable washers 32 may be inserted therebetween as best shown in Fig. 7.

The ends of the pipe sections 11 when turned up tightly within the couplings leave gaps 33 therebetween which ordinarily expose the threads 13 to the action of the well fluids, but to overcome this difficulty each coupling is provided with a ring 34 of the resilient insulating material and which is compressed between the ends of the adjacent pipe sections to assure leak-tight joints therebetween. The rings 34 also assure resistance to backward turning of the pipe sections.

In order to prevent contact of the sucker rods on the tubing and avoid destruction of the resilient insulating coatings, special guide couplings 35 are provided at spaced intervals along the length of the sucker rods. These couplings may be substituted for the couplings illustrated in Fig. 4 at the points at which the guides are nec-

sary. The couplings 35 include a relatively short length of sucker rod section 36 having box ends 37 and 38 provided with internal threads 39 and 40 to receive the pins on the ends of the adjacent sucker rods. The sucker rod sections 36 have the usual wrench engaging faces 41 and collar-like upsets 42. Mounted on the body of the coupling rod sections are substantially cylindrical guides 43 which are preferably molded thereon and retained from longitudinal movement by the upsets 42 and key slots 44 that connect with an axial channel 45 through which the material flows to the socket ends to provide the resilient abutments 46 and 47 for the pins of the adjacent rod sections. The guides are preferably of slightly smaller diameter than the tubing to allow free movement of the rods and the ends are rounded as at 48 to assure easy entrance thereof into the open upper end of the well tubing as when running the sucker rods into the well. In order to permit free passage of the well liquid, the circumferences of the guides are provided with intersecting flow passages 49 and 49' that extend in criss-crossing relation from one end of the guide to the other as best shown in Fig. 1. With this arrangement, diamond shaped islands 50 are formed between the passageways which give ample contact surface 51 with the tubing to assure sufficient support of the tubing to prevent too rapid wear of the rubbing surfaces.

The screen section may be coated on the inner and outer sides with a synthetic rubber as indicated at 52 and 53 and the openings may be provided with magnesium inserts 54 having ports 55.

In using the structure as above described, the tubing and sucker rods are run into the well in the same manner as conventional tubing and sucker rods so that when the elements are in place and the pump in operation, the metal of the sucker rods and tubing are completely insulated by the coatings and the sucker rod and tubing sections are retained in tight relation with their couplings by the resilient action of the rubber abutting blocks. During reciprocation of the rods, the resilient bodies 43 of the guide couplings move in sliding contact to hold the rods concentric in the tubing.

It is thus obvious that any electric currents that may be carried by the rods are prevented from discharge by electrolytic action to the tubing, consequently, the rods are free of the usual deteriorating effects of such currents and will operate for long periods without the customary hazards usually caused by corrosion and electrolysis.

From the foregoing, it is obvious that I have provided sucker rods and tubing which are amply protected from corrosion and electrolysis ordinarily produced by well fluids and that the threads are kept in tight condition so as to prevent intrusion of the well fluids at these points.

What I claim and desire to secure by Letters Patent is:

1. A coupling for sucker rods having ends provided with internally threaded sockets, a coaxial cylindrical body of electrically insulating material exteriorly encircling the coupling and having an exterior surface provided with flow passages, and resilient abutment means in said sockets, said abutment means being integral with the insulating body.

2. A coupling for sucker rods comprising a rod-like body having internally threaded sockets on the ends thereof with said sockets connected by a coaxial bore through the body, a resilient

material in said coaxial bore and forming bottoms for said sockets, said rod like body having a radial opening in connection with said bore and a cylindrical body of said material having a portion extending through the radial opening and integral with the material in said bore and surrounding the rod-like body.

3. A pony rod comprising a member having a rod like body portion provided with internally threaded sockets on the ends thereof and having an axial bore interconnecting said sockets, said rod like body portion of the sucker rod having spaced apart annular upsets and having slot like openings extending through the said bore intermediate said upsets, a resilient insulating material encircling the rod like body and filling the bore for forming resilient bottoms in said sockets, said material extending through the

slot like openings for integrally connecting the encircling material with the material in the bore.
